Clemir J. Aey, of Lowell, Mass.

Assignor to

The Lowell Manufacturing Company.

Letters Patent No. 1728, dated Mar. 3. 1863.

The schedule referred to in these Letters Patent and making part of the same.

To all whom it may concern:

Be it known that I, Clemir J. Aey, of Lowell, in the County of Middlesex, and State of Massachusetts, now temporarily residing in New York, have originated and designed a new Pattern for carpets or other fabrics, of which the following is a full, clear and exact description, reference being had to the accompanying drawings, making part of this specification.

A, in the centre is a set figure, having 16 arms or projections, in the centre of which is a small octagonal frame enclosing a small rosette. Fig. A, rests on the heavy block of key work B, the frame C, encloses the block B, also the ground of small crosses 1, 2, 3, and 4. 5, and 6, at the sides when matched form a figure similar in form to A, in the centre. The surroundings of figs 5, and 6, are similar in form to those of fig. A. D, is an oblong mottled figure with scalloped ends, and a border of small lines. In the centre of fig. D, are five elongated blocks. 7, and 8, at the sides are halves of figures similar to D. The frame surrounding figs. 5, and 6, at the sides, overlaps a portion of fig. D, and the frame C, overlaps portions of figs. 7, and 8. The spaces between the centre and side figures are occupied by the ground of sprigs and leaves, 9, and 10. The remaining parts of the drawing are sections of figures similar to those before mentioned.

The colors employed for the different portions of the design may be varied to suit the taste and wish of the manufacturer.
